UNITED STATES PATENT OFFICE.

JOHN FRANCIS HARRINGTON, OF HUTCHINSON, KANSAS, ASSIGNOR TO HUTCHINSON EGG CASE FILLER COMPANY, OF HUTCHINSON, KANSAS.

SALT-POURING SPOUT.

Application filed June 30, 1921. Serial No. 481,615.

To all whom it may concern:

Be it known that JOHN FRANCIS HARRINGTON, a citizen of the United States, residing at Hutchinson, in the county of Reno and 5 State of Kansas, has invented a certain new and useful Improvement in Salt-Pouring Spouts, of which the following is a specification.

This invention relates to dispensing packages and more particularly to an improvement in pouring spouts for salt containers and the like.

One of the objects of the invention is to provide a simple and practical pouring 10 spout that may be readily brought into position to facilitate the pouring of the contents of the container in a simple and effective manner without waste, and which may be folded to an out-of-the-way position to provide a cover for closing the discharge orifice of the container when desired.

A further object of the invention is to provide adequate means for holding the spout in position. It frequently happens 15 that the pouring spout must be opened and closed many times before the contents of the container are consumed, and many pouring spouts fail to withstand such frequent manipulation, and thus become damaged or de-20 ranged to the point of being ineffective, and in some instances pull away entirely from the cap of the container. Accordingly, the present invention has in view a novel pouring spout having improved anchoring or se-25 curing means for maintaining the spout in place.

With the above and other objects in view which will more readily appear as the nature of the invention is better understood, 30 the same consists in the novel construction, combination, and arrangement of parts hereinafter more fully described, illustrated and claimed.

A preferred and practical embodiment of 35 the invention is shown in the accompanying drawings, in which:—

Figure 1 is a plan view of the cap of a container showing the improved pouring spout applied thereto and arranged in its 40 closed position;

Figure 2 is a perspective view of the top of a container showing the pouring spout in open position;

Figure 3 is a vertical cross sectional view 45 taken on the line 3—3 of Figure 1; and

Figure 4 is a plan view of the blank from which the pouring spout is formed by folding along the score lines indicated.

Similar reference characters designate corresponding parts throughout the several 50 figures of the drawings.

In carrying the present invention into effect, any suitable and available non-corrod-55 ing material may be used in the formation of the blank from which the pouring spout is formed, as for example, sheet metal, paper, or composition material such as paper and fabric. As shown in Figure 4 the pour-60 ing spout blank A preferably consists of a semi-circular body B provided at one end of its diameter with an offset stop lug or 65 check projection C, while the opposite end portion is formed with a relatively large se-70 curing tab or tongue D.

For the purpose of facilitating the bend-75 ing of the blank into proper shape to form the spout, the body B may be provided with the score lines x and y disposed at right angles to each other, and also the obliquely 80 disposed score line z near one end of the se-85 curing tab portion D. The portion of the securing tab between the score line z and the end of the tab is intended to constitute an anchoring foot to assist in holding the spout to the cap. This anchoring foot constitutes 90 one of the novel and distinctive features of the present invention as will presently appear.

When the body B of the blank is folded 95 along the score line x , the opposite halves of the body may be folded toward each other, and thereby provide the angular 100 troughed pouring spout 1, clearly shown in Figure 2 of the drawings. The securing portion D may then be bent along the score 105 line y to provide a hinge line for the pouring spout, thereby enabling the pouring spout 1 to be fitted to the cap 2 of the container in such a manner that the spout may project through the substantially V-shaped slot in the cap, while the securing member 110 D may be glued or otherwise affixed to the inner face of the cap, and at one side of the discharge orifice 4.

When the securing tab D is connected with 115 the cap 2 of the container by the adhesive above referred to or its equivalent, the se-120 curing member is so arranged that the anchoring foot portion E thereof extends to and along the inside of the rim 5 of the cap

to thereby contact with the inner face of the rim in such a manner that when the cap is applied to the body 6 of the container, the anchoring foot E will be clamped between the upper edge 7 of the body of the container and the rim 5 of the cap. Usually the cap 2 is united with the body of the container by suitable adhesive so that in addition to the securing of the spout to the cap through the medium of the member D, the said spout is held in position by the anchoring foot E being clamped between the upper edge of the wall of the body of the container and the rim of the cap. Thus, a positive and effective anchor is provided for the spout, the same performing its holding function even where the adhesive applied to the face of the member D contacting with the cap becomes loosened through the presence of undue moisture or other conditions.

When the pouring spout is in service position as shown in Figure 2, the check projection C will prevent the spout from swinging out too far, that is out of the slot 3, and when the pouring spout is not in use, the wall 1^a of the spout which carries the check projection will serve as a guide to cause the wall 1^b of the trough to properly seat over the discharge orifice 4, thereby providing an effective closure therefor.

From the foregoing it is thought that the features and advantages of the invention will be readily apparent without further description, but it is desired to emphasize the novel and practical feature of providing the pouring spout with interior anchoring means which positively and reliably interlocks with the seam formed between the cap and the body, or other portion of the container, to hold the pouring spout in position. It will of course be understood that changes in the form, proportion and minor details of construction may be resorted to without departing from the spirit of the invention or scope of the appended claims.

I claim:

1. A pouring spout construction including in combination with the container and its cap a spout body adapted to be carried by the cap adjacent said discharge orifice, and having anchoring means adapted to be clamped between the cap and body of the container.

2. A pouring spout construction including in combination with the container and cap therefor having a discharge orifice, a spout body operating adjacent said discharge orifice and having an anchoring extension including a portion adapted to be clamped between the upper edge of the wall of the body of the container and the interior rim of the cap for the container.

3. A pouring spout for containers including in combination with the container body and a dispensing cap therefor, a spout body interior securing means carried by the spout and consisting of a relatively wide portion adapted to parallel the inner face of the cap, and an angularly disposed tip portion adapted to be anchored between the upper edge of the body of the container and the inner face of the rim of the cap.

4. A pouring spout for containers formed from a blank consisting of a body of substantially semi-circular formation and foldable on an intermediate line to produce an angular spout portion, said body being provided at one corner with an offset stop projection while the opposite corner is formed with an integral securing tab of extended area, and the end of said tab being provided with a fold line for forming an anchoring foot.

5. A pouring spout for containers including in combination with the container and cap therefor having an opening; a spout proper consisting of a pair of convergently related wings operating in slots adjacent the opening, a stop projection carried by one of said wings and lying in the plane of said wing at the inside of the cover, a securing tab of relatively extended area integral with the other wing and adapted to be secured to the inner face of the cover to firmly anchor the spout for hinging on a line between the wing and the tab; and an angular anchoring foot carried by the end of the tab and adapted to be clamped between the body and rim of the cover.

In testimony whereof I hereunto affix my signature in the presence of two witnesses.

JOHN FRANCIS HARRINGTON.
